UNITED STATES PATENT OFFICE

BENJAMIN S. HENDRICKSON, OF ASBURY PARK, NEW JERSEY

HAIR WAVING DEVICE

Application filed January 22, 1930. Serial No. 422,628.

This invention relates to an improved hair waving device for marcelling and curling the human hair, and it has more particular reference to an appliance of this class embodying self-contained steaming and conditioning means.

In carrying the invention into practice, I have developed a light-weight electro-mechanical appliance of a portable nature which is constructed to readily receive and firmly clamp and curl the batch of hair, said structure being characterized by simplicity and economy and being susceptible of practical application and removal, and capable of fulfilling the requirements of a structure of this class in a satisfactory manner.

In carrying the inventive conception into practice, I have manufactured a novel composite structure characterized by a novel cartridge including self contained heating means receptive of a chemical solution which when reacted upon by the heat is converted into a steam for conditioning the portion of hair wound on said cartridge.

An additional feature in the construction is a safety jacket which embraces the cartridge and which constitutes a container and retention device for a wetted pad surrounding the wound hair on said cartridge.

In addition, I have found it expedient to provide an appropriate clamping and supporting structure on which the jacket and cartridge are assembled and maintained in feasible relationship for efficient results.

Other features and advantages will become more apparent from the following description and drawings.

In the drawings:

Figure 1 is a sectional view of the complete assembly, showing the mechanical relationship of the details.

Figure 2 is an elevational view of the removable cartridge and its associated elements.

Figure 3 is a cross sectional view on the line 3—3 of Figure 1.

Figure 4 is a top plan view of the clamping and mounting device showing the sections thereof open.

Figure 5 is a top plan view of the same device with the sections closed.

Figure 6 is an end elevation of the structure seen in Figure 1.

Figure 7 is a fragmentary elevational view showing certain of the details.

The clamping and mounting device of the structure is generally designated by the reference numeral 8. It comprises a pair of companion sections 9 and 10 respectively. These are of general rectangular form. The section 10 includes a pad 11, a metal plate 12, and a rubber protective and abutment strip 13. The section 9 includes a similar pad 14 and a plate 15. The aforesaid plate 12 has a lateral extension 16 at one end with which the section 9 is pivotally connected as at 17 in Figure 4.

Also the plate 12 carries a rigid upright 18 having a bearing hole formed therein. Pivoted as at 19 to the opposite end of the plate 12 is a connecting link or strip on which is carried a complementary upright 21. The upright 21 has a notch at its upper end for reception of a journal. This link 20 carries a latch 22 pivoted thereon as at 23. The latch serves to hold the sections of the clamp in clamping relationship as seen in Figure 5.

The upright 21 is provided with a pivoted pawl 24. A spring 25 serves to hold the pawl in operative relationship as seen in Figure 6. An important unit of the structure is the cartridge generally designated by the reference character 26 as seen in Figure 2. This comprises a tube of the shape shown, said tube being designated by the numeral 27 and including a longitudinal row of steam discharge ports 28.

At the left hand end is a journal 29 mounted for rotation in the seat in the upright 21. On the extremity is an insulated fitting 30 with which the source of electric supply (not shown) is connected. At 31 is a ratchet wheel with which the pawl 24 is engageable as seen in Figure 6. The internal electric heating element is designated by the numeral 32. The numeral 32a designates a metal gauze sleeve or screen placed within the curling rod and surrounding the heating element. This element is designed to aid in maintaining the chemical liquid against unrestrained discharge through the ports 28.

Incidentally, it is to be stated that under many conditions the liquid employed is somewhat of a pasty nature for which reason the screen is particularly important in insuring an orderly maintenance and restricted discharge, of the chemical vapors.

In the right hand end of the tube as seen in Fig. 1, is a plug which is constructed to accommodate a spring pressed ball check valve 33 providing a chamber for introducing the chemical solution. This plug is formed with a pintle or journal as at 34 mounted for rotation in the aforesaid upright 18.

I next call attention to the numeral 35 which designates generally a jacket including complementary sections 36 and 37 hinged together by a spring hinge as at 28. These sections embrace the cartridge 26. The end portions 39 of the cartridge are shaped to form bearings for the cylindrical end portions 40 of this jacket. Incidentally, the jacket is intended to provide a container for the usual flannel pad (not shown) which is saturated in the conventional way with a chemical solution.

In practice, the electrical source of supply is connected with a fitting 30 to operate the heating element 32 within the cartridge. The portion of hair to be treated is brought up between the sections 9 and 10 of the clamping device when they are in the open position seen in Figure 4 and is then wrapped appropriately around the cartridge 26.

The chemical solution is introduced into the cartridge by way of the valved inlet 33. An important feature to be noted in this connection is the discharging of the chemical steam through the discharge ports 28 for conditioning the hair in an effective and characteristic manner. Assuming that the cartridge is assembled on the clamping frame, the jacket 35 is placed in position, and prior to this the usual flannel pad is saturated and placed therein to surround the hair which has been previously wound on the cartridge.

The entire device as a whole rests upon the head with the rubber pads 11 and 14 bearing thereagainst as a protective means. The pawl and ratchet means serves to hold the cartridge in a set position to prevent unwinding of the hair.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

I claim:

1. In a hair waving device of the class de-

scribed, a cartridge comprising a hollow tube provided with a row of steam discharge ports, a fitting arranged at one end of said tube and including an electrical socket connection and an electrical heating element projecting into said tube and co-extensive with the steam discharge ports, and a plug fitted into the opposite end of said tube, said plug being formed with a journal and a valved chamber for introduction of a chemical solution.

2. In a hair waving device of the class described, a cartridge comprising a hollow tube provided with a row of steam discharge ports, a fitting arranged at one end of said tube and including an electrical socket connection and an electrical heating element projecting into said tube and co-extensive with the steam discharge ports, and a plug fitted into the opposite end of said tube, said plug being formed with a journal and a valved chamber for introduction of a chemical solution, said tube being of cylindrical formation and constituting bearings, and an embracing and projective jacket comprising a pair of symmetrical half sections hinged together and having annular journals at their opposite ends embracing said bearings.

In testimony whereof I affix my signature.

BENJAMIN S. HENDRICKSON.
